UNITED STATES PATENT OFFICE

2,419,460

ELECTRICAL SOCKET

Kenneth M. McLaughlin, Summit, N. J., assignor
to Radio Corporation of America, a corporation
of Delaware

Application December 31, 1942, Serial No. 470,735

6 Claims. (Cl. 173—328)

1

My invention relates to electrical sockets, particularly to sockets adapted for radio tubes and the like.

The object of my invention is an improved socket which is strong, simple in construction, inexpensive to manufacture, and is adapted for easy assembly with its supporting chassis.

The male element with which my novel socket is particularly adapted is the type having a plurality of relatively long and slender contact pins circularly arranged on a base. One embodiment of my socket comprises an insulating disc which carries circularly arranged female contactors, and a sheet metal annulus, U-shaped in cross section, with two coaxial spaced cylinders joined at their upper ends by an integral ring, the inner cylinder being coaxial with but slightly larger than the circle of contact pins. Hence the pins are guided over the socket contactors while they are rotated to the proper position for insertion. The outer cylinder extends downwardly beyond the lower end of the inner cylinder and may be formed inwardly to hold the insulating disc in place.

The characteristic features of my invention are defined in the appended claims and preferred embodiments thereof are described in the following specification and shown in the accompanying drawing in which:

Figures 1 and 2 show longitudinal sectional views of my improved socket and its relation to a typical radio tube base;

Figure 3 is a top view of the socket shown in Figures 1 and 2;

Figure 4 and Figure 5 are, respectively, plane views of the top and bottom insulating discs for carrying the socket contactors, and

Figure 6 is another socket embodying my invention.

The male element chosen for illustration with my socket is a typical radio tube comprising an envelope 1 closed at its lower end with a glass base or header 2 carrying contact pins 3, the pins being parallel and circularly arranged in the header about a central tipped-off exhaust tube 4.

The socket contactors 5 are carried in the usual manner on a thin disc, web or sheet 7 of strong fibrous insulating material. The contactors may comprise strips of metal with punched out holes 5a in registry with the holes 7a of the insulating disc 7, and may conveniently be clamped in place by a second disc or web 6 having holes 6a aligned with the punched holes of the contactors. The contactor strips preferably extend radially outward and pass downwardly through apertures 7b

2

in the bottom disc. Notches in the edges of the discs may be used to rotationally orient the discs with each other and with a supporting metal annulus hereinafter more fully described.

5 The body portion of the socket, which holds the insulating discs and is fixed in the chassis of the equipment using the radio tube, comprises an annulus 8, having a metal cylinder 8a joined at its upper end to an inwardly extending integral ring 8b. An inner cylinder 8c may, if desired, be extended downwardly from the inner edge of the ring 8b as shown in Figure 1 or Figure 2 so that the annulus, in cross section, is substantially U-shaped. The discs are rigidly held in place in the sheet metal annulus by inwardly rolling, spinning or die pressing the sheet metal stock of the outer cylinder 8a over the peripheral edge portions of the discs 6 and 7. The inner diameter of the metal ring 8b, and 10 of the inner cylinder, if used, is only slightly greater than the diameter of the circle of the contact pins of the male element so that the ends of the pins may be inserted into the socket and freely rotated. If desired, the ends of the contact pins may be held out of contact with the discs by a shoulder or radial projection 9 so that the pins can be inserted only when the base is in the proper rotational position over the socket. This shoulder slides smoothly along the top surface of the metal ring 8b as the tube base and pins are rotated until the shoulder drops into the keyway 8d in the metal ring, whereupon the tube base may be pressed home. The keyway becomes a slot when inner cylinder 8c is employed. Alternatively, the projection may comprise the outwardly bent end 10 of one of the pins as shown in Figure 2. If desired, a tubular metal shield 11 may be centrally mounted in the socket and provided with a side arm 12 for contacting the indexing or locating pin to electrostatically shield the socket contactors and base pins. Elongated holes 6b and 7b in the insulating disc accommodate the side arm 12 and receive the indexing pin.

45 The horizontal radially extending ring portion 8b of the annulus may be so proportioned in size that the rim of the tube base comes to rest upon its upper surface as shown in Figure 6. Alternatively, the ring portion may be provided with an 50 upwardly extending fold 8e as shown in Figures 1 and 2 and adapted to fit inside the envelope and bear against the glass header. The bottom of annulus 8 may be flanged around the chassis base as at 8f.

55 Rivets, bolts and other fastening means for

fastening my improved socket into its chassis are advantageously eliminated. The lower end of the outer cylinder is passed downwardly through a punched hole in the chassis plate, whereupon the lower rim $8f$ of the outer cylinder is folded outwardly to rigidly anchor the socket in place.

My improved socket body is conveniently and inexpensively made by die drawing the U-shaped annulus and its various folds from thin sheet metal. Cold drawn sheet iron .015 to .025 inch thick may be drawn into socket bodies having an overall diameter of about one inch with relatively light punch presses. Progressive punches are particularly adapted for automatically drawing the socket bodies of my invention. The continuity of the metal portions of the socket from the metal chassis to the rim of the envelope insures effective shielding of the base pins and socket contactors from outside electrical disturbances.

I claim:

1. An electrical socket for contact members comprising a sheet metal cylinder, an insulating disc extending transversely across one end of the cylinder and secured to the walls thereof, female contactors for said member arranged in a circle and carried by said disc, the other end of the cylinder being formed inwardly into a metal ring spaced from said disc, the inner peripheral portion of said ring being coaxial with and sufficiently larger in diameter than the circle of contactors carried on said disc to produce clearance for said members while maintaining substantial alignment of said members in the circle of said contactors.

2. In an electrical socket for contact members a sheet metal annulus comprising a metal cylinder, an insulating disc in said cylinder extending across the lower end of the cylinder, said cylinder being formed inwardly over the top and bottom peripheral portions of said disc to secure said disc in said cylinder, said disc having a series of holes arranged in a circle coaxial with said cylinder, and female contactors for said members in line with said holes, the upper end of said cylinder being formed inwardly into an integral ring with the inner rim coaxial with the cylinder and sufficiently large to produce clearance for said members while maintaining substantial alignment of said members in the circle of said contactors.

3. An electrical socket for contact members comprising a drawn sheet metal cylinder having at one end an integral in-turned flange, an insulating disc in said cylinder extending across the cylinder parallel to said flange, the wall of

said cylinder at circumferential points spaced from said flange being crimped over the peripheral portions of said insulating disc to rigidly secure the disc in the cylinder spaced from said flange, a plurality of female socket contactors for said members arranged in a circle coaxial with and substantially smaller in diameter than the inside diameter of said flange.

4. An electrical socket comprising a drawn sheet metal cylinder, said cylinder being reversely bent to telescope inside the upper end thereof and then bent to form an in-turned flange, said flange extending radially of, and substantially normal to, the longitudinal axis of the cylinder, whereby the fold in the cylinder extends upwardly above the surface of the flange, an insulating web across the lower end of the cylinder, and contactors carried on said web.

5. An electrical socket comprising two coaxial spaced cylinders joined at their upper ends by an integral ring, the outer cylinder extending axially below the lower end of the inner cylinder, an insulating disc in the outer cylinder extending across the end of the inner cylinder, the outer cylinder at circumferential points below the lower end of the inner cylinder being crimped around said insulating disc, the disc having a series of holes arranged in a circle coaxial with and smaller in diameter than said inner cylinder, and female contactors in said holes.

6. An electrical socket comprising two coaxial spaced cylinders joined at their upper ends by an integral ring, an insulating disc extending across the lower ends of said cylinders, the outer cylinder being folded at circumferential points below the lower end of the inner cylinder around the peripheral portion of said disc to rigidly secure said disc therein, a plurality of female contactors arranged in a circle coaxial with and inside said inner cylinder, said contactors being insulatingly supported on said disc.

KENNETH M. McLAUGHLIN.
